CLAIM

We claim the ornamental design for the all-terrain vehicle, as shown and described.

DESCRIPTION

FIG. 1 is a left front perspective view of body panels and a roof for an all-terrain vehicle of the present disclosure;
 FIG. 2 is a right rear perspective view thereof;
 FIG. 3 is a left side view thereof;
 FIG. 4 is a right side view thereof;
 FIG. 5 is a top view thereof;
 FIG. 6 is a front view thereof; and,
 FIG. 7 is a rear view thereof.

The portions of the vehicle and the vehicle components shown in broken lines form no part of the claimed design.
